UNITED STATES PATENT OFFICE.

THOMAS WILLIAM TWYFORD, OF HANLEY, COUNTY OF STAFFORD,
ENGLAND.

DESIGN FOR A WATER-CLOSET BASIN.

SPECIFICATION forming part of Design No. 17,432, dated July 5, 1887.

Application filed May 14, 1887. Serial No. 238,275. Term of patent 7 years. Registered in England August 27, 1886, No. 55,420.

To all whom it may concern:

Be it known that I, THOMAS WILLIAM TWYFORD, a subject of the Queen of Great Britain, and residing at Hanley, in the county 5 of Stafford, England, manufacturing potter, have invented a new and original Design for Water-Closet Basins or Pans, of which the following is a specification, reference being had to the accompanying drawing, forming a 10 part thereof.

The figure is a perspective view of my newly-designed pan or basin.

Heretofore basins or pans have been made of somewhat the conformation or shape as the 15 pan itself, or the conformation of the pan or basin with the main outlets and the trap, which, when viewed in elevation, exhibit these features. The whole of these parts are concealed from view (when in use) by an outer in- 20 closure or covering.

The leading features of my design consist in the shape of the pillar, the scalloped or struck-up work upon the pillar, and the design upon the bracket and parts above the 25 bracket in which the down pipe terminates.

a is a pillar, which is rectangular in its general contour, (and horizontal section,) but with rounded-off corners, and particularly so at the back end.

b are raised struck-up scalloped scrolls or 30 struck-up surfaces or surfaces in relief upon the said pillar, while *c* is a less raised pattern surrounding the boundary of the foot, and *d* is a slightly raised pattern upon the front of the pillar, while the said pillar is supported by a 35 foot, *e*, partially fluted near its extreme base.

Having thus described my design, I claim as new and desire to secure by Letters Patent—

The design for a water-closet basin or bowl, as shown and described, consisting of a base, *a*, 40 ornamented upon the outer surface with raised patterns *b* and *c* upon the sides, scroll pattern *d* upon the front, and partially-fluted base-piece *e* surrounding the lower end, as set forth.

Dated this 26th day of April, 1887.

THOMAS WILLIAM TWYFORD.

Witnesses:

ARTHUR BENSON,
EDWIN TAYLOR,

Both of Hanley, in the county of Stafford.
